(57) **CLAIM**

I claim the ornamental design for a telescoping reset/testing tool with interchangeable heads, as shown and described.

DESCRIPTION

FIG. 1 is a perspective view of a first embodiment of the telescoping reset/testing tool with interchangeable heads.

FIG. 2 is a front view of the first embodiment, and the rear view is a mirror image thereof.

FIG. 3 is a right side view of the first embodiment, and the left side view is a mirror image thereof.

FIG. 4 is a top view of the first embodiment.

FIG. 5 is a bottom view of the first embodiment.

FIG. 6 is a perspective view of a second embodiment of the telescoping reset/testing tool with interchangeable heads.

FIG. 7 is a front view of the second embodiment.

FIG. 8 is a right side view of the second embodiment.

FIG. 9 is a left side view of the second embodiment.

FIG. 10 is a top view of the second embodiment.

FIG. 11 is a bottom view of the second embodiment.

FIG. 12 is a perspective view of a third embodiment of the telescoping reset/testing tool with interchangeable heads.

FIG. 13 is a front view of the third embodiment, and the rear view is a mirror image thereof.

FIG. 14 is a right side view of the third embodiment, and the left side view is a mirror image thereof.

FIG. 15 is a top view of the third embodiment; and,

FIG. 16 is a bottom view of the third embodiment.
